ABSTRACT

This disclosure relates to a high frequency field effect transistor with and accurately aligned gate contact disposed between source and drain contacts. The device consists of a substrate having a substantially flat upper surface, a layer of lightly doped semiconductor material having its bottom surface disposed on the surface of the substrate and a metal layer disposed on the upper surface of the layer of semiconductor material. An aperture is formed through the metal layer into the layer of semiconductor material. The gate contact is disposed within the aperture while the metal layer around the periphery of the aperture form the source and drain contacts.

ATTORNEY

2. depositing a metal layer to one surface of the epitaxial layer, said one surface being parallel to the surface of the epitaxial layer in contact with the substrate,
3. disposing a layer of photoresist on the metal layer,
4. developing a pattern in the photoresist,
5. etching away a portion of the metal layer to form source and drain contacts,
6. etching an aperture through a remaining portion of the metal layer,
7. etching an aperture in the epitaxial layer below the metal layer, said remaining portion of the metal layer being

- used as a mask for said etching, and
8. affixing a metal contact to the epitaxial layer within the aperture.
2. The process of claim 1 in which the epitaxial layer is grown to a thickness of from 4 to 5 microns and is doped to a concentration of from 10^{14} to 10^{16} atoms of dopant per cubic centimeter of semiconductor material.
3. The process of claim 2 in which the substrate is p-type silicon, the epitaxial layer is n-type silicon, and the metal layer 10 consists of gold.
